UNITED STATES PATENT OFFICE

2,493,955

PORTABLE WASHING PLANT

Walter A. Erickson, Anchorage,
Territory of Alaska

Application December 13, 1945, Serial No. 634,753

6 Claims. (Cl. 104—126)

1

This invention relates to ore washing apparatus, one of the objects being to provide a complete washing unit which, in spite of its size and weight, can easily be shifted from place to place within the area of operations without necessitating dismantling.

A further object is to provide apparatus of this character which, by reason of its peculiar construction, can be moved by "walking" it from place to place simply by changing the position of the center of gravity so that opposite sides can be relieved alternately from excessive weight, thereby permitting the lightened side to be advanced following each shift of the center of gravity.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings, the preferred form of the invention has been illustrated.

In said drawings,

Figure 1 is a front elevation of the complete apparatus.

Figure 2 is a top plan view, one of the positions assumed during the "walking" operations being indicated by broken lines.

Figure 3 is an enlarged section on line 3—3, Figure 2.

Figure 4 is an enlarged section on line 4—4, Figure 2.

Figure 5 is an enlarged elevation of the upper or feed end of the apparatus, some parts being removed and other parts being broken away.

Figure 6 is an enlarged perspective view showing one of the upper pivotal connections of the track portions of the apparatus.

Figure 7 is an enlarged perspective view illustrating one of the pivotal connections of the braces forming a part of the supporting structure.

Figure 8 is a horizontal section through a portion of a sluice box illustrating its pivotal connection with the carriage at the upper or feed end thereof.

Figure 9 is a front elevation of the carriage at the upper end of the apparatus, portions being broken away to show the pivotal connections between the carriage and the sluice box.

Figure 10 is a vertical transverse section through the supporting carriage adjacent to the

lower or delivery end portion of the sluice box and showing the adjustable supports for the sluice box.

Figure 11 is a side elevation of the structure shown in Figure 10.

Referring to the figures by characters of reference, 1 designates parallel skids of any suitable proportions and materials and secured to these skids adjacent to their ends are front and rear standards 2 and 3 which support top beams 4 having braces 5 extending therefrom to the standards as shown particularly in Figure 3.

The two supporting frames formed by the skids, standards and top beams, are joined by front and back cross beams 6 each of which, as shown

particularly in Figure 6, has a hinge plate 7 which

extends between the flanges of the adjacent beam 4 and is held thereto by a hinge pin 8. For the purposes of reinforcement braces 9 and 10 are

secured to each end portion of each beam 6, these braces being rigidly secured to the beam at their upper ends and being preferably disposed parallel to each other as shown, for example, in Figure 1. Hinge plates 11 are attached to the

lower ends of the braces and have offset ends 12 which, as shown in Figure 7, extend between ears

13 in the adjacent standards 2 or 3 and are held thereto by hinge pin 14. Thus it will be noted that the two supporting frames and the front

and rear cross beams with their braces, cooperate

to form a parallelogram capable of being flexed in planes at right angles to the axes of the several hinge pins.

It is to be understood that, for the purpose of

insuring requisite strength, the several standards, top beams and cross beams can be fabricated from a desired number of rigidly connected angle members. The specific construction of these parts constitutes no part of the present invention.

Elongated track plates are mounted on and move with the cross beams. These plates, which have been indicated at 15, are parallel with each other and their ends can be extended desired distances beyond the side supporting frames. A

rear track 16 is secured on and extends longitudinally of one of these track plates while a front track 17 is secured on and extends longitudinally of the other plate 15.

A carriage 18, illustrated in detail in Figures 8 and 9, is provided with supporting wheels 19 mounted on the track 16 and mounted on and pivotally joined to the carriage 18 by means of a king bolt 20 is a turntable 21 provided with side standards 22 and mounted on arcuate bearing plates 23.

Another carriage 24 having supporting wheels 25, is mounted on the track 17 and this carriage is provided, adjacent opposite portions thereof, with guides in the form of standards 26 each of which has a bearing 27 slidably mounted therein and adapted to be guided in its up and down movement by studs 28 slideable within slots 29 in the standards. A cross rod 30 can be located in each standard for limiting the downward movement of each of the bearings.

The two bearings 27 mounted in the standards 26 are connected to and adapted to be actuated by hydraulic jacks 31 adapted to be actuated simultaneously for the purpose of raising or lowering the bearings.

A roller 32 is mounted on a shaft 33 which extends through slots 34 formed in the standards 26 and is carried by the bearings 21. This roller constitutes a rotatable support on which rests one end portion of a sluice box 35 which, as shown, can be provided with lateral extensions 36 having openings 37 through which the standards 26 are extended loosely.

The washing and separating apparatus assembled with the sluice box does not, in itself, constitute any part of the present invention. It might be stated briefly that one end of the sluice is equipped with a feed hopper 38 opening downwardly to a grizzly 39 which, in turn, is positioned to feed material to a trommel 40 positioned to deliver tailings to laterally extended rock chutes 41.

Any suitable construction and arrangement of riffles 42 is provided in the sluice box whereby screenings from the trommel will be thoroughly washed and separated.

A suitable power plant 43 can be located at one side of the sluice structure between the carriages and side platforms or walks 44 can be extended along the sides of the sluice box. These can be provided with hand rails 45 and can even be extended to steps 46 whereby access can be had readily to an elevated platform 47 above the hopper 38.

The power plant 43 is designed to transmit motion through shafting 48 to a drum 49 which, as shown, is mounted on the carriage 24 and has wrapped about it an intermediate portion of a cable 50. This cable is supported on guide pulleys 51 located at the respective ends of the track 16. From these pulleys the ends of the cable are extended toward each other and are fastened to opposite portions of the carriage 24. Thus when the drum 49 is rotated in one direction, the carriage will be moved toward one end of its track whereas, when the drum is rotated in the opposite direction, the carriage 24 will be moved toward the other end of its track 16.

For the purpose of preventing the carriage supported apparatus from running off of the tracks provided therefor, the track 17 can be provided with terminal abutments or chocks 52.

Any suitable arrangement of water pipes 53 can be employed and obviously the power plant is to be provided with suitable controls by which the carriage supported structure can be moved desired distances toward one end or the other of the tracks.

It is to be understood that the present apparatus is designed primarily for large operations and, accordingly, the capacity of the mechanism must be considerable. Ordinarily, a machine of this size would have to be set up in a permanent position and the materials hauled thereto and delivered therefrom, thereby prolonging greatly the

operations carried out. The purpose of the present invention is to permit the use of a large apparatus of great capacity which is capable of being moved from place to place so that it will always be in position to receive the ore at the point of excavation. The movement of the apparatus is effected in the following manner:

The carriage supported structure mounted on the rails is shifted by means of the cable 50 until it is brought close to one end of the two tracks. This places the center of gravity over or close to one of the skids. Thereafter a tractor or the like is connected to one end of the other skid which, being relieved of the great weight of the sluice box and the mechanisms associated therewith can be pulled forwardly without disturbing the position of the other skid. This is due to the fact that the supporting structure is in the form of a parallelogram and when one skid is pulled forwardly the cross beams 6 and the tracks thereabove will swing forwardly with the shifted skid. Upon the completion of this step in the advancement of the apparatus, the carriage supported structure is shifted along the tracks toward the other end thereof so that the center of gravity is brought above or close to the skid which had been moved. This lightens the load on the skid which had not been shifted and it thus becomes possible to hitch a tractor or the like to that skid and pull it forwardly. Obviously, by following this step by step operation, the entire apparatus, even though of great weight, can be "walked" forwardly or backwardly as preferred so that the apparatus thus can be maintained close to the material as it is being excavated.

An important feature of the invention is found in the fact that the sluice box can be moved from side to side to bring it to any desired angle so that the tailings can be handled without moving the entire machine and so that various widths of pay streaks can be handled without moving the entire machine.

What is claimed is:

1. Transporting apparatus for ore treating apparatus comprising a supporting structure having the form of a parallelogram when viewed in plan, said structure including two pairs of parallel members, the members of one pair being pivotally connected at their ends to the members of the other pair; shiftable supports beneath and connected to the members of one pair; carriage means mounted on the members of the other pair; turntables on said carriage means for supporting ore treating apparatus; and means for shifting said carriage means bodily from one side to the other side of the supporting structure, said sides being defined by the members of said first named pair, thereby to position the center of gravity of ore treating apparatus supported upon said carriage means above the shiftable supports successively.

2. Transporting apparatus for ore treating apparatus comprising supporting elements; a supporting structure mounted on said elements and comprising four beams pivotally connected at their ends to constitute a parallelogram when viewed in plan, said supporting elements being positioned under two opposite beams of said structure; parallel tracks mounted on and vertically aligned with the other two beams of said structure; carriage means mounted on the tracks; turntables on said carriage means adapted to support ore treating apparatus; and means for moving the carriage means bodily along the tracks to position the center of gravity of the

ore treating apparatus carried thereby substantially in line with one or the other of the supporting elements.

3. Transporting apparatus for ore treating apparatus including a supporting frame comprising two pairs of pivotally connected members forming a parallelogram when viewed in plan; spaced supporting elements for said frame connected to and below the opposite members of one pair, said elements being mounted for alternate movement in one direction, thereby to "walk" the frame from one position to another; carriage means rollably mounted on the opposite members of the other pair; supports for ore treating apparatus pivotally mounted on said carriage means; and means for shifting said carriage means bodily along the members of said second-named pair from one side of the supporting frame to the other side, said sides being defined by the members of the first-named pair, thereby alternately to position the center of gravity of ore treating apparatus supported upon the carriage means substantially in line with the respective supporting elements.

4. Transporting apparatus for ore treating apparatus comprising a supporting structure comprising pivotally connected members forming a parallelogram when viewed in plan; supporting elements beneath and connected to two opposite side portions of said structure and positioned to be advanced successively in one direction, thereby to "walk" the structure in said direction; carriage means rollably mounted on the other two opposite side portions of said structure; revolvable platforms mounted on the carriage means and adapted to support ore treating apparatus mounted on the structure; and means for moving said carriage means bodily along the last-named side portions in either of two directions, to position the center of gravity of the supported ore treating apparatus substantially in vertical alignment with one or the other of said supporting elements.

5. Transporting apparatus for ore treating apparatus comprising a supporting structure including pivotally connected members forming a parallelogram when viewed in plan; skids under and connected to two opposite members of said structure, said skids being positioned for successive movement in one direction, thereby to

"walk" the structure in said direction; parallel tracks mounted on and vertically aligned with the other two opposite members of said structure; carriage means rollably mounted on the respective tracks; platforms revolvably mounted on the carriage means and adapted to support opposite ends of ore treating apparatus extending between the tracks; and means for moving said carriage means toward either end of the tracks, thereby to shift the center of gravity of the ore treating apparatus carried thereby into substantial vertical alignment with one or the other of the skids.

6. Transporting apparatus for ore treating apparatus comprising parallel skids; standards secured to and extending upwardly from the skids; a pair of parallel beams secured to and supported by the standards; a second pair of parallel beams pivotally connected at their ends to the beams of the first pair, said pairs of beams cooperating to provide a parallelogram when viewed in plan, said parallel skids being disposed below and in substantial vertical alignment with the beams of the first pair; parallel tracks mounted upon the beams of the second pair in substantial vertical alignment therewith; a carriage rollably mounted on each of the tracks; a turntable on each carriage, the turntables being adapted to support opposite ends of ore treating apparatus extending between the carriages; and means for shifting the carriages toward either end of the tracks, thereby to shift the center of gravity of ore treating apparatus supported thereupon substantially into vertical alignment with the respective skids.
